Des. 198,353
Patented June 2, 1964

198,353

OIL BURNER

Robert G. Richardson, West Springfield, Mass., assignor
to Gilbert & Barker Manufacturing Company, West
Springfield, Mass., a corporation of Massachusetts

Filed Jan. 24, 1963, Ser. No. 73,301

Term of patent 14 years

(Cl. D81—2)

Des. 198,353

PAGE 2

Fig. 3.

Fig. 4.

Fig. 5.Fig. 6.FIG. 1 is a side elevation of an oil burner embodying my new design;

FIG. 2 is a fragmentary top plan view thereof;

FIG. 3 is a side elevation showing the side thereof opposite that shown by FIG. 1;

FIG. 4 is a front elevation thereof;

FIG. 5 is a rear elevation thereof; and

FIG. 6 is a fragmentary plan view of the bottom thereof.

The dominant features of the design reside in the portions shown in full line.

I claim:

The ornamental design for an oil burner, as shown and described.
